United States Patent Office.

JOSHUA G. ALLEN, OF PHILADELPHIA, PENNSYLVANIA.

Letters Patent No. 63,452, dated April 2, 1867.

IMPROVED SPIRIT METER.

The Schedule referred to in these Letters Patent and making part of the same.

Be it known that I, JOSHUA G. ALLEN, M. D., of the city of Philadelphia, and State of Pennsylvania, have invented a new and useful Machine or "Spirit Meter" for the purpose of ascertaining and registering the exact amount and the strength or proof of the spirits flowing from the still, and for the purpose of separating the high from the low wines at any stage of the distillation that may be desired; and I do hereby declare that the following is a full, clear, and exact description of the construction and operation of the same, reference being had to the annexed drawings, making a part of this specification, in which—

Figure 1 is a front view.

Figure 2 is an end view.

Figure 3 is a plan.

Figure 4 is a sectional view.

Figure 5 is an end view of one detached hydrometer chamber with its stop-cock and cams.

These are views of the machine when constructed for registering temperature, specific gravity, and volume of the spirits passing through it.

Figure 6 is a front view.

Figure 7 is a sectional view.

Figure 8 is a back view; and

Figure 9 is a plan.

These are views specially exhibiting the modifications of the machine when it is constructed for registering weight in addition to specific gravity, temperature, and volume, as above.

A, pipe leading from still to first meter.

B, branch pipe leading to a second meter.

C, three-way cock.

D, pipe passing under hydrometer chambers and from three-way cock to cistern.

E, pulley-wheel on which weight is wound.

F, pipe leading from pipe D on to cistern.

G, float chamber.

H, hydrometer chambers.

I, glass tubular portion of hydrometer chambers.

K, screw-bolts for fastening and securing glass tubes and metallic caps.

L, escapement lever.

M, upper arm of escapement lever.

N, lower arm of escapement lever.

O, hole or perforation in lower arm of escapement lever, through which float-pan rod passes.

P, button or knob on float-pan rod.

Q, float-pan rod.

R, float pan.

S, escapement wheel.

T, lower tooth or pawl of escapement lever.

U, upper tooth or pawl of escapement lever.

V, hydrometer in hydrometer chamber.

W, arms attached to hydrometer-chamber cocks, operated on by cam-wheels.

X, metallic caps or disks, forming tops and bottoms of hydrometer chambers.

Y, cams that open hydrometer-chamber cocks.

Z, cams that shut hydrometer-chamber cocks.

a, cog-wheel on same axle as cams that open hydrometer-chamber cocks.

b, cog-wheel turned by cog-wheel a.

c, cog-wheel with interrupted spaces on same axle as cog-wheel b.

d, cog-wheel with interrupted spaces on same axle as cog-wheel a.

e, cog-wheel attached to three-way cock, acted on alternately by cogs c and d.

f, air hole in top of hydrometer chamber.
 g, bevel-gear cog on lower end of perpendicular axle, acting on bevel gear h.
 h, bevel-gear cog on axle of cams that shut hydrometer-chamber cocks.
 i, bevel-gear cog on axle turned by the weight.
 k, bevel-gear cog on perpendicular axle conveying motion to bevel-gear cog h and cams Z.
 l, cog on axle of cam z, turning cog m, and axle n, and the cams Y.
 m, cog on axle of cams Y, turned by cog l.
 n, axle of cams Y and cog m, turned by cog l.
 o, axle of cam Z, and cogs a and d and l.
 p, axle of cogs b and e, turned by cog-wheel a on axle o.
 q, discharge pipe through which cistern is emptied.
 r and s, stop-cocks for regulating which cistern shall be receiving spirits from still.
 r is in pipe leading to first cistern and meter, and s is in branch pipe leading to second cistern and meter.
 t, weight acting as motive power.
 u, axle or shaft on which the pulley-wheel of weight is placed.
 v, hydrometer-chamber cocks.
 w, weighing board or scale board on which cistern is placed.
 x, perpendicular rod forced up when cistern descends.
 y, triangular projection or flange on rod X.
 z, triangular projection or flange on float-pan rod Q.
 G', float chamber when constructed as an apartment of cistern.
 S', escapement-wheel or ratchet-wheel, on its side.
 L', escapement lever when placed on its side or working horizontally.
 T' and U', teeth or pawls of escapement lever, when placed on its side.
 F', flexible portion of pipe leading from pipe D to cistern.
 H', cistern on scale board.
 K', weight on scale board.
 M', lever which raises perpendicular rod X.
 N', axle of bevel-gear cogs k and g.
 The motive power for operating the machine in these drawings is represented as a weight, which will probably be found practically the most convenient.
 The nature of my invention consists of an instrument, or machine, or meter, to be connected, by means of a pipe or pipes, with a reservoir or cistern, of any convenient size, in which the product of the still is contained while being measured. This machine or meter has a three-way cock or valve, through which the product of the still must flow, both in passing into and filling the cistern and meter, and also in passing out of and emptying them. This three-way cock or valve is turned so as to let the spirits into and out of the cistern at the proper moment, and is regulated, in connection with other stop-cocks or valves pertaining to other parts of the meter, by means of appropriate machinery to be presently described.

In order to avoid the corrosive effects of the acetic and other corrosive acids always present in the product of the still during the process of distilling alcoholic or vinous liquors, the various stop-cocks or valves herein used and described are to be made of glass, hard or vulcanized rubber, gold, silver, platinum, aluminum, or similar non-corrosive metals, or of substances coated over or plated with non-corrosive metals.

There is also a series of graduated glass tubes, of any convenient number and length, so arranged and connected with the cistern as to be filled with the liquid passing from the still to the cistern, to the same level or height as that at which the liquid at any given time rises or stands in the cistern, thus at all times showing the exact depth of liquid in the cistern. Each glass tube contains a hydrometer, thus showing the exact strength or proof of the spirits in the cistern. Each glass tube is furnished with an ordinary stop-cock or valve so arranged, turned, and worked by appropriate machinery, as to shut off and retain for inspection and examination the liquid which has passed into the tube with which the cock thus turned is connected.

These glass tubes I shall hereafter describe and allude to as hydrometer chambers. The stop-cocks of this series of hydrometer chambers are arranged by appropriate machinery so as to be closed successively, one after the other, one being closed each time the cistern becomes full; and this closing of the hydrometer-chamber cock or valve is arranged to occur just at the moment the three-way cock or valve is turned into such position as to empty the cistern. By this means one hydrometer chamber is kept reserved and retained filled to the same level as that at which the spirits stood in the cistern at the moment of its beginning to be emptied, and it being a graduated tube it can be ascertained in a moment the number of inches in depth that either are or have been in the cistern; whence its contents are exactly known. As each hydrometer chamber contains a hydrometer, the exact strength or proof likewise becomes known. We have thus both the quantity and proof registered, and the registry and contents of each hydrometer chamber may be retained any necessary length of time for repeated inspection. Now just at the moment the cistern is emptied, the machinery attached again changes the three-way cock or valve into such a position as will allow the cistern and meter to be refilled, and when full, as before, by the same process again shuts off and reserves another hydrometer chamber as full of spirits as the cistern has again been filled, and so on.

From ten to forty or even a greater number of hydrometer chambers may be thus successively filled, indicating a like number of cisterns full of spirits. These hydrometer chambers are constructed by pressing the ends of the glass tubes, previously nicely cut and ground smooth, firmly upon elastic vulcanized rubber

disks or washers, fitted at each end and surmounted with metallic plates, firmly held together and in position by means of rods or screw-bolts of sufficient length. A small air-hole is left in the top cap and disk, and the bottom cap and disk is perforated with a hole sufficiently large to let the spirits pass freely in and out of the hydrometer chamber, which is thus formed by the glass tubes, caps, disks, and screw-bolts, just described. The hole in the lower or bottom end of the hydrometer chamber is connected with the stop-cock v , and the stop-cock v with the pipe D , connecting with the cistern H' , and with the three-way valve.

In order to call the motive power into operation at the proper moment, so as to move the various parts of the machinery as herein indicated, there is, in addition to the three-way cock and the hydrometer chambers, with their cocks already described, an upright tube or tubular vessel, G , its bottom extending slightly below the bottom of the cistern and hydrometer chambers, and being at least equal to them in height. This we shall call a float chamber G . It is in direct connection, by means of pipes D , with the cistern and hydrometer chambers H , and the three-way cock or valve C is attached to it, close to its bottom, which must be slightly below the level of the bottom of the cistern, so that when the three-way valve is open the whole apparatus may be completely emptied, except, of course, those hydrometer chambers in which the liquid is intentionally retained for examination.

Fitting and moving loosely in this float chamber there is an empty water-tight pan, R , or vessel, or float, which it is evident will be raised, floated, or buoyed up in the float chamber G , as the whole gradually fills with spirits. This we shall call a float or float pan. A straight rod projects from the top of this float or float pan, making it much resemble a piston fitting loosely in the float chamber. This rod Q passes through a hole, which acts as a guide in the top or corner of the float chamber, and has a button, P , or knob, on the upper end, so as to answer designs presently to be described.

All the valves v or stop-cocks of the hydrometer chambers are turned and regulated by a system of cam-wheels Y and Z , a well-known and familiar mechanical arrangement. The cam-wheels are in this drawing connected by a well-known cog-wheel bevel-gear movement, (many forms of which might be devised, all answering the same end,) with an escapement wheel, S , which holds the whole machinery quiescent, by means of the teeth or pawls of an escapement-lever, L , which catch alternately in the escapement-wheel almost exactly like the action of the well-known escapement movement of watches and clocks.

These teeth or pawls which thus regulate and control the motion of the escapement-wheel and attached machinery, are on the short end of a lever; the other, or long end of the lever, is bifurcated or divided into two arms, and is made to come exactly over the centre of the float chamber, one arm above the other. The lower arm of the long end of the lever is perforated, O , so as to allow the stem or projecting rod of the float pan to pass through it.

Now it is evident by referring to the drawing that as the liquid from the still enters through the pipe A , and three-way valve C , the cistern, hydrometer chambers, and float chamber will be filled, and the float pan in the float chamber will be raised or floated up so that the button or knob P , on the upper end of the projecting rod Q , will come to impinge on the upper arm of the long end of the escapement-lever so as to lift it up and release the escapement-wheel from the pawl attached to the upper end of the lever, as seen in fig. 4. Immediately in obedience to the impulse of the attached weight, the escapement-wheel and all connected machinery will turn; but, in lifting the long arm of the escapement-lever, the lower pawl is lifted also, and the ratchet is quickly caught on this lower tooth or pawl, and thus its motion is stopped and regulated exactly after the manner of the escapement-movement in clocks and watches; but the escapement-wheel is allowed to move far enough, before being thus stopped, to turn the attached machinery into such position as to close the cock of and thus retain the spirits in one hydrometer chamber. Simultaneously with thus closing of one hydrometer-chamber cock, the three-way cock or valve is turned and changed so as to allow the cistern to empty, and to stop further flow of liquid into either meter or cistern from the still.

The machinery is now quiescent till the cistern is emptied, when it is evident that the float pan will fall in the float chamber until the knob on the upper end of its rod comes to impinge on the lower arm of the long end of the lever, thus bringing the weight of the float pan to operate so as to draw down the long end of the lever, till the pawl or tooth attached to it slips down and allows the escapement-wheel to turn till caught in the other pawl or tooth of the short arm; but during this turn of the machinery the three-way valve is also changed so as to allow the cistern to fill again, and so on till all the hydrometer chambers are filled. By means of the shape and position of the cams which turn and regulate the hydrometer-chamber valves, at the moment of the filling of the last hydrometer chamber of the series the cocks of one, two, or three, or any convenient number of the hydrometer chambers first filled, may be turned so as to empty them, ready for refilling. The instrument will then only need occasional winding up of the weight, for as the machine goes on its regular round, one of those hydrometer chambers longest since filled will be emptied, and so on in succession, as the series begins to refill.

By this means each hydrometer chamber can be kept filled many days for examination by different inspectors and detectives, as a check upon each other. The meter is to be kept under lock and seal and examined through a glass window. Even if surreptitiously opened, it cannot be safely tampered with, as it must either go its regular round or be broken.

It will be noticed that when the three-way cock or valve is turned into such position as to empty the cistern, the flow from the still will be stopped. In order to prevent the spirits being, at this time, dammed back into the worm and still, another reservoir or cistern of small size is provided, which may be simply an enlargement of the pipe leading from the worm to the three-way valve, and merely of sufficient capacity to contain the product of the still during the few minutes the spirits are running out of the cistern. With this provision the arrangements are complete.

Now, in order to separate the high from the low wines, it is only necessary to have an ordinary stop-cock, r , fixed at any convenient position in the pipe leading from the small reservoir to the three-way valve C, and a branch pipe, B, leading off just above this stop-cock, and between it and the still. This branch pipe leads off to another and second meter and cistern, identical with the first in construction and working. This branch pipe leading to the second meter, has also an ordinary stop-cock a short distance below its junction with the main pipe from the still. While the high wines are passing over, one can be left open and the other shut, thus allowing them to pass into whichever cistern the owner may elect. When the low wines begin to flow, which may be known by watching the meter, the cocks can be reversed, thus turning them into the other cistern. These cocks are under the control of the owner of the still, and thus as many divisions may be made as he may desire.

Concerning the mechanical movements of the meter, it is only necessary to point out that the escapement-wheel is turned by a weight, t , which communicates its motion, by means of the bevel-gear cogs $i k g h$, to the axle o , on which one set of cams, which act upon the hydrometer-chamber cocks, so as to shut them, is placed. This axle or shaft, by means of a plain cog-wheel connection, turns the axle n of another set of cams, y , which act on the hydrometer-chamber cocks, so as to open them. Another cog-wheel, d , is placed upon the axle o , first mentioned; this has a portion of its cogs missed or cut out, so as to act interruptedly upon the cog-wheel which turns the three-way cock or valve C. A third cog-wheel, a , is on the same axle, o , which turns another cog-wheel, b , of the same size on the axle p ; this axle p has on it another cog-wheel, c , exactly like the cog-wheel d , having similar interrupted spaces. These cog-wheels c and d , with interrupted spaces, turn in opposite directions, and act at interrupted intervals upon the cog-wheel e attached to the three-way cock C, opening and shutting it at the proper moment, so as first to fill the cistern, and then to empty it. The turning of the hydrometer-chamber cocks may be changed, regulated, and varied indefinitely, and almost infinitely, according to the shape and position of the cams Y and Z. The action of the float upon the lever and its pawls or teeth, and its connection with the ratchet, have been already sufficiently explained.

In cases where extreme accuracy is demanded or desired, so that the actual weight of all liquid flowing from the still is required, in addition to its volume and specific gravity, the instrument should be constructed and modified in the following manner, figs. 6, 7, 8, and 9. The float chamber should be placed within the cistern, or made to become simply a compartment thereof, and freely communicating therewith by means of numerous passages or openings, through which the liquid occupying the cistern may pass in and out of the float chamber, or float-chamber compartment G'. The three-way valve is made in direct connection with the pipe passing beneath and communicating with the hydrometer chambers without passing through the float chamber as before, but the cistern is connected with the other end of the pipe passing beneath the hydrometer chambers just as before; but instead of being placed indifferently as regards its direction from or proximity to the meter, as was possible before, the side or portion of the cistern, in which is placed the float chamber, is brought to occupy nearly the position which would have been convenient, suitable, or necessary for the float chamber to occupy when the meter was constructed as previously described, and the whole cistern must be seated upon and in this position immovably fastened to one end of a sort of scale-board or scale-beam, resting and working upon a pivot or hinge, so as to admit of a weight being placed, suspended, or used on the other end in order to weigh or balance it.

Now in the portion of the cistern used as a float chamber, or rather formed into a float chamber, a float pan is placed as before; but the rod connected with this float pan is only allowed to act upon the escapement-lever when it descends, and not also when it ascends, as before described in fig. 4. Now while the cistern is empty, or while filling, until it reaches in weight the amount designed for it to contain, which is regulated by the weight K' upon the other end of the scale-board or steel-yard, the cistern will be raised or kept up, but as soon as the cistern is filled so as to balance the weight K' on the opposite end, it will first come level and next quickly descend. I desire especially to point out that it will quickly descend, and not vibrate irregularly, and the following is the reason: It will be observed that so long as the cistern is lighter than the weight, the cistern will be kept in such a position that it will lean towards the weight; the liquid in the cistern will thus be deeper on the side of the cistern towards the weight than on the other side of the cistern, but as soon as the amount equal to the weight flows into the cistern its tendency will be to depart from its leaning position and become level. But the instant the scale or balance-beam on which the cistern is placed begins to approach a level, the depth and amount of liquid on the side of the cistern from the weight rapidly increase, and this adds greatly to the leverage on the cistern end of the balance-beam, and causes a steady, certain, and rapid descent of the cistern; and the further it descends the greater this leverage becomes, because the slant or lean of the cistern is reversed, and the liquid in it constantly grows deeper and heavier on the end of the scale-board from the weight, and adds to its force in that direction and causes a more and more certain and rapid descent. Now as the cistern thus descends it is made to act upon and force upward a perpendicular rod, x , almost exactly resembling the rod projecting from the float pan. This rod stands perpendicularly upon one end of a lever to which it is fastened by a hinge joint, and is raised or forced up in consequence of the cistern in its descent striking against and forcing down the opposite end of the lever M' upon which this rod thus stands; this is very clearly illustrated in the drawing, fig. 7.

It will thus be easily perceived that the rod of the float pan can be used precisely as before described to pull down the escapement-lever as the cistern empties, and thus allow the machinery and valves to turn so as to refill it, and that when full, or containing the number of pounds intended, the descent of the cistern will quickly force up the other perpendicular rod so as to raise the escapement-lever just as the float-pan rod raised it before, and again turn and regulate the machinery and valves so that the cistern will empty and retain a specimen in the hydrometer chambers for examination. If it is found desirable, the escapement-lever can be

moved from side to side, or laterally, instead of, as heretofore described, only up and down or perpendicularly. In this case the escapement-wheel, upon which the escapement-lever acts, must be placed upon its side or horizontally. It will do if placed upon the perpendicular axle or shaft N' , connecting the bevel-gear wheels k and g , and used for conveying the motion from the horizontal axle or shaft upon which the weight is wound to the axle or shaft upon which the cam-wheels for turning the hydrometer-chamber cocks are placed. The lever is then moved from side to side by the following device: Upon the upper end of the rod projecting from the float pan a triangular-shaped projection, z , is placed, one of its straight sides being fastened securely to the edge of the projecting rod, the apex or most acute angle being placed directly downward and its base or broader part upward; the free edge of this projection or flange thus slants upward and off from the rod. This can easily but only be understood by referring to the drawing. The escapement-lever is placed in such position that as the float pan descends, this projecting edge will push the lever to one side. Nearly facing or opposite this float-pan rod the other perpendicular rod x , before spoken of as being forced up as the cistern descends, is placed, and at a proper position on it is fastened a flange or triangular projection, y , exactly like that on the float-pan rod, except that it slants in an opposite direction, namely, downward and off from the rod. Thus the escapement-lever is pushed off from this perpendicular rod when it ascends, and, as will be readily comprehended by referring to the drawing, the escapement-lever is thus pushed to and fro from side to side, giving it a lateral motion, instead of a perpendicular motion as before, in one direction as the cistern is emptied, and the other as it fills. This lateral motion is only suggested, because it is possible that an escapement-lever, working perpendicularly, might be found more likely to slip from its position than a lateral motion.

The plan giving the absolute weight has the only advantage that weight is in all cases rather more reliable than measure; but its disadvantages are that the cistern must be in close proximity to the meter—in fact a part of it—and the whole must be kept locked up, and there is a temptation and possibility to enter surreptitiously and load the scale, and thus defraud. The advantage of the specific gravity and volume meter is that only the meter need be locked up. There is never any necessity to open it except for repairs, which are not likely to be needed if well made. There is no temptation to open it, as the meter can only be altered by breaking it and endangering, nay, insuring, detection.

The cistern can be a tightly-enclosed vessel (except an air-hole, a line in diameter, too small to tamper with it,) and may be located at some convenient distance from the meter, requiring only to be kept on the same level as the meter, or a known variation from it. The inaccuracy of its measure can be reduced practically to nothing when specific gravity and temperature are given, as is done by this meter. By having, say, thirty hydrometer chambers to each meter, and the cistern as large as the possible capacity for the still to fill in one day, the record of each cistern full is kept for a month at least. The distiller can be required to report the state of his meter and pay his tax every week. The internal revenue collector for each district can then send his officer to see that it is given correctly, and the Department can employ and follow these with as many detectives as necessary, at irregular and occasional intervals, so as to make fraud too dangerous and hazardous to practise to any serious extent.

I do not claim the escapement-movement, or the cog-wheels, or cam-wheels, as being either novel or new, or, simply as an escapement, or cog-wheel, or cam-wheel, as being my invention, but what I claim as my invention, and desire to secure by Letters Patent, is—

1. The application of the escapement-movement, consisting of the lever L , acting upon the ratchet-wheel S , or its equivalent, for the purpose of regulating, controlling, and calling into action the motive power and machinery used for turning and working the stop-cocks and valves, constructed substantially in the manner herein described and set forth.

2. The bifurcation or division into two arms, M and N , of one end of the escapement-lever L , constructed substantially in the manner and for the purpose herein set forth.

3. The hole or perforation O , in the lower arm of the escapement-lever L , for the purpose of allowing the rod Q of the float or float pan R to pass through it.

4. The application of the float or float pan R , constructed substantially in the manner herein set forth, and used for the purpose of regulating, moving, and controlling, or aiding in regulating, moving, and controlling the escapement-lever L , and attached machinery.

5. The series of glass tubes or hydrometer chambers H , constructed substantially in the manner and for the purpose herein set forth.

6. The graduation of the hydrometer-chamber tubes H , and their connection with the receiving cistern so as to indicate the depth or amount of liquid in the cistern.

7. The application of a stop-cock, v , or its equivalent, with each hydrometer chamber, so arranged, moved, turned, and worked, by appropriate machinery, as to keep secure and retain for a variable period of time a specimen of the liquid or spirits that are or may have been in the cistern.

8. The application of cam-wheels Y and Z , for the purpose of thus turning, working, and regulating the hydrometer-chambers' stop-cocks or valves v , constructed and acting substantially in the manner herein described and set forth.

9. The combination and connection of this series of hydrometer chambers H , with the three-way cock C , or an equivalent valvular arrangement, for regulating the ingress and egress of the spirits to and from the meter, constructed substantially in the manner and for the purpose herein set forth.

10. The application of the interrupted cog-wheel e d , for the purpose of turning, regulating, and reversing the three-way valves, as herein described and set forth.

11. The arrangement of two or more spirit-meters, with a corresponding number of cisterns, each and all leading to the main pipe A , coming from the same still, with a plain ordinary stop-cock, r and s , at a suitable

and convenient place in each pipe thus leading to the main pipe A, coming from the still, as herein described and set forth.

12. The combination and connection with each other of the various parts of the machine herein described and claimed, constructed substantially in the manner and for the purpose herein set forth;
